UNITED STATES PATENT OFFICE.

EDMUND DAVIS GROVE, OF OAKLAND, CALIFORNIA.

COMBINED TEETER AND ROUNDABOUT.

1,392,147.

Specification of Letters Patent. Patented Sept. 27, 1921.

Application filed May 17, 1920, Serial No. 382,108. Renewed May 19, 1921. Serial No. 470,951.

To all whom it may concern:

Be it known that I, EDMUND D. GROVE, a citizen of the United States, residing at Oakland, in the county of Alameda and State of California, have invented new and useful Improvements in Combined Teeters and Roundabouts, of which the following is a specification.

One object of my present invention is the provision of a combined teeter and roundabout of simple, durable and safe construction.

Another object of the invention is the provision of a combined teeter and roundabout embodying means whereby the operation of the apparatus may, when deemed expedient, be limited to teeter operations, as when it is desired to put a stop to the roundabout capacity of the apparatus by way of punishment for some infraction of rules.

To the attainment of the foregoing, the invention consists in the improvement as hereinafter described and definitely claimed.

In the accompanying drawings, hereby made a part hereof:

Figure 1 is a plan view showing my combined roundabout and teeter construction.

Fig. 2 is a side elevation of the same.

Fig. 3 is a diametrical section through the central portion of the apparatus.

Fig. 4 is a detail view illustrative of the arrangement of the cushioning springs relatively to the arms of each teeter.

Figs. 5 and 6 are detail views illustrative of the locking provision.

Similar numerals of reference designate corresponding parts in all of the views of the drawings.

At 1 is a vertically disposed sleeve maintained in position above a base 2 through the medium of stays 3, that are fixed to auxiliary bases 4. All of the bases referred to may be and preferably are formed of concrete.

Journaled in the sleeve 1 and stepped at its lower end in the base 2 is an upright post 5. The said post is preferably of three inch pipe, capped at its upper end and having its lower end plugged with Babbitt metal to afford an anti-friction wearing surface.

Pivottally mounted on the post 5 at different points in the height thereof and arranged at angles to each other are teeters 9, each of which has a central opening 10 receiving the post 5 and sufficiently large for the required vertical oscillation of the teeter

on the post. Each teeter 9 is provided, in the preferred embodiment of my invention, with bearing blocks 11. Fixed to it at opposite sides of its opening 10, and extending transversely through each pair of bearing blocks 11, and diametrically through the post 5 is a tube 12, preferably of three-fourth inch pipe, and a bolt 13, said bolt 13 being headed at one end and equipped with a nut 14 at its opposite end.

Fixed to the post 5 at diametrically opposite points and arranged under the arms of each teeter 9, are springs 15, there being two of the said springs to each teeter, and the springs being connected to the post 5 through the medium of a diametrical joint 16, and each spring having a curvilinear arm arranged under and in vertical alignment with one of the teeter arms. The springs 15 serve to cushion the downward movements of the teeter arms, and in that way contribute to the elasticity of the teeter action and the pleasure of those using the teeters. It will also be appreciated that the springs 15 are safety factors, inasmuch as they preclude forcible striking of the teeter arms against the ground, as when weight is suddenly removed from one arm of a teeter, while weight is still imposed on the other arm thereof.

By virtue of the mounting of the revolute post 5 in the manner described, it will be observed that the children on the teeter arms may use the apparatus as a roundabout, it being simply necessary for each child as it reaches the ground, to exert a sidewise push with one foot against the ground, whereby the post 5 and the parts carried thereby will be revolved about their common axis.

At 20 is a rectilinearly movable bolt equipped with an eye 21 at its outer end and movable into and out of an aperture 22 in the revolute post 5. Manifestly when the said bolt 20 is disposed in the aperture or socket 22 of the post 5, the apparatus is held against rotation and can then be used only as a teeter.

In combination with the said bolt 20, the outer portion of which is in the form of an upwardly directed arm 23, I employ a hinge that comprises a member 24 fixed to the base 2, and a vertically swinging member 25. The said member 25 is provided with two claws 26 adapted to drop and rest at the opposite sides of the bolt 20, and then when a

suitable lock 27 is secured in the eye 21 above the member 25, it will be manifest that the post 5 will be locked against turning. This provision is advantageous, inasmuch as it renders it convenient to penalize children when guilty of some infraction of rules to the extent of limiting the operation of the apparatus to the teeter operation.

Having described my invention, what I claim and desire to secure by Letters-Patent, is:

1. In a combined teeter and roundabout, the combination of an upright revoluble post, a base, means supporting the post, a teeter fulcrumed on and extending in opposite directions from the post, and means including a member connected to the base, a member detachably engaged with the first named member and engaging the post, and a lock to secure the second-named member against detachment from the first-named member whereby the post may be secured against unauthorized release for rotation.

2. In a combined teeter and roundabout, the combination of an upright revoluble

post, means supporting the same, a teeter fulcrumed on and extending in opposite directions from the post, a bolt movable rectilinearly into and out of engagement with the post and having an upturned outer arm terminating in an eye, and a hinge including a fixed member and a vertically swinging member having claws adapted to rest at opposite sides of the bolt arm below the eye thereon, whereby when a lock is secured in the eye the post and the parts carried thereby will be locked against rotation.

3. The combination of an upright post, a teeter having an opening in which the post is disposed, said teeter being pivotally connected to the post, and cushioning springs having inner portions opposed to and fixedly connected with the post and also having curvilinear arms reaching from the lower ends of the inner portions and disposed under and in alignment with the arms of the teeter.

In testimony whereof I affix my signature.

EDMUND DAVIS GROVE.
